SHOE

Alfred De Stefan, Binghamton, N. Y., assignor to
Louis Smoller, Bronx, N. Y.

Application March 17, 1932, Serial No. 599,376

7 Claims. (Cl. 36—16)

My present invention relates generally to shoes, and more particularly to a novel manner of assembling the shoe parts and to a shoe so produced.

5 I have illustrated my invention as embodied in the shoe known as the "stitched down" shoe, and in which there is employed an inner-sole, a mid-sole and an outer-sole and a false welt all assembled with the lining and the upper of a 10 shoe. It will be understood, however, that the inclusion of any or all of these parts is necessitated by my invention only when called for by the language of the claims.

15 It is a general object of my invention to provide an arrangement for the assembly of the shoe parts which enables the production of a shoe more quickly and more economically than hitherto, and does not require skilled labor of the type hitherto employed, and also to the production of a 20 new shoe by the employment of this process.

For the attainment of these objects, and such other objects as may hereinafter appear or be pointed out, I have illustrated one embodiment of my invention in the drawing, wherein:

25 Figure 1 is a cross section through the front part of a shoe, made in accordance with my process;

Figure 2 is a cross-section of the upper and the lining assembly before its association with the other parts;

30 Figure 3 is a cross-section of the inner and mid-sole assembly, before its association with the other parts;

Figure 4 is a cross section through the toe portion of the shoe illustrating the step in the process of associating the assemblies of Figures 2 and 3;

35 Figure 5 is a cross section similar to Figure 4 showing a further step whereby, the outer-sole is associated with the assembly of Figure 4; and

Figure 6 is a cross-section similar to Figure 4, but showing the finished shoe as it appears after the performance of the final step.

40 Figures 2, 3, 4 and 5 are illustrative of steps in the assembly of the shoe, and it will be understood that, as to the disclosure of these steps, they do not necessarily represent all the steps that may be necessary for the completion of the shoe, nor does their order as given herein represent the order in which the steps are or must be 45 performed, nor is it intended to limit the process either to the inclusion of all of these steps or to the order disclosed, unless called for specifically by the language of the claims.

50 The assembly of Figure 2 is of the upper 10

and the lining 11. It will be understood that as to this illustration and as to the illustration in the other figures, that they are more or less diagrammatic, but yet understandable to anybody skilled in the art.

55 In Figure 3, I show the inner sole 15, and the midsole 16 associated together in any preferred or desired manner as by an adhesive or binder 17. It will be observed that the inner sole 15 is made narrower than the mid-sole 16, so as to have the 60 mid-sole extend laterally beyond the inner sole, and is associated therewith approximately symmetrically thereof. In the formation of this assembly, the binder 17 need be applied sufficiently only to cause the members 15 and 16 to 65 adhere to each other for convenience of manufacturing, and also for fixing the association of the parts for wearing purposes.

70 Figure 4 is intended to represent my manner of associating the assemblies of Figures 2 and 3, 75 and this I accomplish by bringing down the terminal side portions 11' and 11² of the lining member 11 into the associated relation to the assembly of Figure 3, such as shown in this Figure 4. These side terminal portions of the lining member 80 are brought down more or less into lateral association with the inner-sole member 15 and then bent into parallel association with the top surface of the side terminal portions of the mid-sole 16 which extend beyond the inner-sole 15, 85 and in dotted lines in this Figure 4, I show the mid-portion in the condition in which it is shown in Figure 3, and before it is trimmed off in the manner I will now set forth.

90 The side terminal bent portions of the lining 11 above referred to, are permanently secured to the mid-sole as by stitching 18 clearly shown in Figure 4. The side terminal portions of the lining and mid-sole assembly are then trimmed off. The dotted lines in Figure 4 are intended to represent those portions which are removed in this trimming operation. The extent of the trimming operation is more or less determined by the position of the stitches 18.

95 In Figure 5, I show a step in connection with the assembling of the outer-sole 20 with the assembly of Figure 4. The outer-sole 20 is brought into association with the partial assembly of Figure 4 somewhat in the manner shown in Figure 5. It will be observed that the outer-sole is of 100 a greater extent laterally than the mid-sole, and is in contacting relation with the mid-sole. There are thus provided side extensions 20' and 20² and the upper 10 has the lateral portions 10' and 10² bent into parallelism and into contacting 105

110

relation with the upper surfaces of these extensions 20' and 20², and the associated relation of the parts as shown in Figure 5 may be maintained for the next operation in any preferred or desired manner as by use of the binding material 22.

In Figure 6, I show a further step, and from the aspect of the disclosure of my invention, the final step in my process. The welt strip 25 dimensioned and contoured so as to permit of its association in superimposed relation to the parts 20' and 20², 10' and 10², as shown in Figure 6, is then positioned as shown in this figure, and these three superimposed parts secured in fixed relation in any preferred or desired manner, as for example, by passing stitches 27 therethrough.

In this manner, I attain the general objectives of my invention because all of the steps herein disclosed are steps that do not require a high order of skill, and can be performed rapidly, efficiently, and economically and a product is attained by the practice of my invention, which it is believed, presents advantages over those hitherto known.

Having thus described my invention and illustrated its use, what I claim as new and desire to secure by Letters Patent, is:

1. The process of manufacturing a shoe which comprises assembling a lining and an upper, assembling an inner-sole with a mid-sole having its perimeter extending laterally therebeyond, and securing the lining to said extending portion of the mid-sole, securing an outer-sole wider than the mid-sole to the assembly by securing the perimeter of the upper to that portion of the outer-sole which extends beyond the mid-sole.

2. The process of assembling an upper and a lining, with an inner-sole, mid-sole and outer-sole, which are successively of increasing surface dimensions in the order named, which process comprises the following steps: bringing together the inner-sole and the mid-sole to provide an extending perimeter to the mid-sole, securing the outer portions of the lining in superimposed relation to said extending perimeter of the mid-sole, bringing the outer-sole into associated relation to the thus far formed assembly to provide the outer sole with a perimetrical extension, and securing the free edge of the upper to said extending portion of the outer sole.

3. The process of assembling an upper, and a lining, with an inner-sole, mid-sole and outer-sole, which are successively of increasing surface dimensions in the order named, which process comprises the following steps: bringing together the inner-sole and the mid-sole to provide an extending perimeter to the mid-sole, securing the outer portions of the lining in superimposed relation to said extending perimeter of the mid-sole

simultaneously trimming off the superfluous superimposed parts of the lining and the mid-sole to the desired extent, bringing the outer sole into associated relation to the thus far formed assembly to provide the outer-sole with a perimetrical extension, and securing the free edge of the upper to said extending portion of the outer-sole.

80

4. A shoe comprising an inner-sole and a mid-sole associated in superimposed relation with the mid-sole extending laterally beyond the inner-sole, an upper, and a lining having its free lower end bent into superimposed relation to the extending portion of the mid-sole and in edge-abutting relation to said inner-sole, and the upper extending beyond the lining and into edge-abutting relation to the mid-sole.

85

5. A shoe comprising an inner-sole and a mid-sole, associated in superimposed relation with the mid-sole extending laterally beyond the inner-sole, an upper, and a lining having its free lower end bent into superimposed relation to the extending portion of the mid-sole and in edge abutting relation to said inner-sole and secured thereto, and an outer-sole wider than the mid-sole positioned so as to have it extend laterally beyond the mid-sole, the lower free end of the upper and a welt strip being secured to the extending portion of the outer sole.

90

6. A stitched-down shoe comprising an inner-sole, a mid-sole and an outsole superimposed in the order named, and progressively increasing in size so that their successive excess portions form a run surrounding the superjacent portion, said inner-sole being united to the mid-sole, a lining secured to the mid-sole, an upper extending beyond the mid-sole and the lining and in edge-abutting relation thereto, said upper having a portion overlying the exposed rim of the outer-sole, a welt strip overlying the upper where it contacts the outsole, stitching uniting the welt strip, upper and outsole, and binding material uniting the upper and the outsole at the point where they overlie.

105

7. A shoe comprising an inner-sole and a mid-sole associated in superimposed relation with the mid-sole extending laterally beyond the inner-sole, an upper, and a lining having its free lower end bent into superimposed relation to the extending portion of the mid-sole and in edge-abutting relation to said inner-sole, and an outer-sole wider than the mid-sole positioned so as to have it extend laterally beyond the mid-sole, the lower free end of the upper being secured to the extending portion of the outer sole, in edge-abutting relation to said mid-sole.
